UNITED STATES PATENT OFFICE

148,958

DESIGN FOR A MAIL BOX

Harris W. Robinette, Chicago, Ill.

Application September 21, 1946, Serial No. 133,490

Term of patent 3½ years

(Cl. D74—9)

To all whom it may concern:

Be it known that I, Harris W. Robinette, a citizen of the United States, residing at Chicago, in the county of Cook and State of Illinois, have invented a new, original, and ornamental Design for a Mail Box, of which the following is a specification, reference being had to the accompanying drawings, forming a part thereof.

In the drawings:

Fig. 1 is a front perspective view of a mail box showing my new design;

Fig. 2 is a right side view; and
Fig. 3 is a top view thereof.

I claim:

The ornamental design for a mail box, substantially as shown.

HARRIS W. ROBINETTE.
